UNITED STATES PATENT OFFICE.

JOHN P. EULBERG, OF CHICAGO, ILLINOIS, ASSIGNOR OF ONE-HALF TO FREDERICK W. WITTENMEIER, OF CHICAGO, ILLINOIS.

CAN-TOP AND THE LIKE.

1,333,297.

Specification of Letters Patent.

Patented Mar. 9, 1920.

Application filed April 9, 1919. Serial No. 288,793.

To all whom it may concern:

Be it known that I, JOHN P. EULBERG, a citizen of the United States, residing at Chicago, in the county of Cook and State 5 of Illinois, have invented certain new and useful Improvements in Can-Tops and the like, of which the following is a description.

My invention relates to the usual closure used upon the various types of metal cans, 10 in which the top is an integral whole flanged down at the edges to embrace the proximate edges of the body, the two being secured together with solder or equivalent material.

In cans having liquid contents, it is common 15 to punch a hole in the can-top at some suitable point and pour the liquid out. Such of course, however, is usually unsanitary and unsatisfactory for the reason that the liquid will work along the top of the can

20 and from thence over the edge and down the side, ultimately reaching the bottom where it is conveyed to whatever part the can is placed upon, spotting the cloth or the dish in which the can may be placed, leaving 25 a portion at the top which changes with atmospheric conditions, and leaving an opening in the can which permits the admission of atmosphere and a modification of the contents. Also if the pouring opening 30 is not close to the edge, it is almost impossible to completely empty the can, leaving a portion therein which is lost.

Cans for such use, are such as those used 35 for evaporated cream, syrup, oils, and various liquids of that type.

The object of my invention is to provide a novel top which without materially increasing the cost of the can or top, will largely obviate the difficulties referred to.

40 To this end my invention consists in the novel construction, arrangement and combination of parts herein shown and described, and more particularly pointed out in the claims.

45 In the drawings, wherein like reference characters indicate like or corresponding parts,

Figure 1 is a perspective view of the common type of milk or cream cans embodying my invention;

Fig. 2 is an edge view of said top, illustrating my invention;

Fig. 3 is a diagram illustrating the manner in which circular can tops are laid out

and stamped from the sheet, and showing 55 that the inclusion of my improved top is gained without the loss of material;

Fig. 4 is a similar view illustrating another method of laying out the can tops on the sheet;

Fig. 5 is a perspective view illustrating the application of my improved top to a so-called "square" can, and including an improvement as to the opening therein;

Fig. 6 is an enlarged view of the spout 65 and indicated opening, showing one means of forming the opening;

Fig. 7 is a view similar to Fig. 6 showing a slight modification;

Fig. 8 is a section substantially on line 70 8-8 of Fig. 6, illustrating a cork in position in the opening; and

Fig. 9 illustrates the method of laying out the square can top above on the sheet, showing how the spout may be provided 75 without loss of material.

In the drawings, 1 represent an ordinary cylindrical or circular can in general use, and 2 the top, which is flanged down in the usual manner at the periphery as at 80

3 to embrace the top of the body 1 to which it is secured with solder in the usual manner. These tops 2, when laid out upon the sheet, usually lead to loss and waste at the interstices between the adjacent circular portions.

I employ this usually waste material by forming it into an extension 4, which ultimately forms the spout. After the body is stamped out, it is flanged downward as at 5 in the usual manner, including the part 90

5 carrying the spout extension 4. The spout extension is then given a reverse bend as at 6, preferably being pressed tightly against the part 5 and given a slight spout curve as indicated.

This forming is all done upon the dies with but slight change from the present method to provide for the spout. At the same time and for the class of cans

in which liquids are usually employed, I prefer to indicate a point in close proximity 100 to the spout at which the top should be punched for pouring purposes. This is also done in the dies, and is indicated in close relation to the position of the spout as at 7.

A second depression as at 8 may also be 105 indicated, where a slight puncture for the admission of air will insure a free pouring of the liquid out of the opening 7.

It is obvious in the first place that there is no increase in the cost of material for the reason that the spout is made out of that portion of the material that is now absolute waste. It is also obvious that there is no increase in the expense for forming the top, as it is done in substantially the same manner as it is done at the present time, and with no increase in expense. It 10 is also obvious that the soldering operation will be the same, so that my improved can top may be formed and employed without any additional expense either as to material or as to manufacture.

15 In the method shown in Fig. 3, the circular can tops may be laid out on the sheet in what is known as the staggered form, while in Fig. 4 they are laid out in what is known as the square form. In each method 20 there is always a loss of material in the interstices between the circular tops, although in the square form of lay-out it is believed that there is less such waste. However that may be, it is immaterial so far as 25 my invention is concerned, as to which method may be employed.

In the form shown in Fig. 5, 9 indicates the so-called square can, and 10 the top thereof. The method of laying the same out 30 is illustrated in Fig. 9, where it will be seen that owing to the circular or rounded corners of the can, sufficient material is found for the spout 11, so that again there is no waste in taking the whole sheet into consideration. In this case also, the edges are 35 flanged downward as at 12, including that portion in proximity to the spout being marked 13, and the reverse bend marked 14. The operation of forming up the flange is 40 the same as heretofore described.

The improvement as to the opening which may be desirable in larger cans in which the entire contents are not removed at once, although it is also adaptable for 45 use in smaller cans where they are not entirely emptied at one use, consists in indicating the opening corresponding to the opening 7 as at 16. In the form shown in Fig. 6, the said depression is constructed to be 50 readily opened or cut along lines 17 extending radially from the center 18. This forms segments 19 which are bent inward from the marginal edges of the opening, forming retaining walls for a cork or compressible 55 closure 20. The thin wall of tin or metal top 10, unless reinforced, is too thin to suitably support a cork which it thereby allows to swing or tilt on the top. In the form shown, the cork is retained sufficiently for practical 60 purposes and may be removed and replaced any number of times. This form is particularly adaptable in the use of oil cans and larger cans containing any material which is emptied gradually and by a series 65 of operations.

As shown in Fig. 7, the point from which the diverging lines extend is not in the center of the opening, serving to support the cork more firmly on one side than the other, and is preferred where the can is 70 large and may be carelessly handled. The proximity of the side wall of the can on the spout side tends to aid in supporting that side.

While my invention rests in the peculiar 75 can top with the integral spout as stated, the improvement in the opening shown in Figs. 5 to 8, is an independent invention well adapted for use with my improved top.

It is apparent that the entire structure 80 can be very economically constructed, and effectively obviates the disagreeable features referred to as in pouring the liquid over the spout, any remaining therein is drained back into the can, and in no case will it flow over 85 and down the side of the can upon the table or support of the can.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned. 90

What I claim as new and desire to secure by Letters Patent is:

1. A can top or the like comprising an integral sheet conforming to the body of the 100 can and provided with a marginal spout extension, the periphery of the top including the part carrying the extension being flanged downward to embrace the top edges of the body, said extension then being reversely 105 bent and lying in proximity to the flange, and slightly curved to form a spout.

2. A can top or the like comprising an integral sheet conforming to the body of the can and provided with a marginal spout 110 extension, the periphery of the top including the part carrying the extension being flanged downward to embrace the top edges of the body, said extension then being reversely bent and lying in close proximity to 115 the flange, and an indicating mark close to the edge and in alignment with the spout, marking the spot where the can is to be opened for pouring the contents out.

3. A can top or the like formed by stamping from a single integral sheet, said can top conforming to the body of the can and provided with a marginal spout extension, the periphery of the top including the part carrying said extension being flanged downward to embrace the top edges of the body, said extension being reversely bent and lying in close proximity to the flange, and an indicating mark close to the edge and in alignment with the spout, said indicating 120 125 130

mark being formed by stamping a part of the material of the top from the surface plane of the top and marking the spot where the can is to be opened for pouring out the 5 contents.

4. A can top formed by stamping from a single integral sheet, said can top conforming to the body of the can and provided with a marginal spout extension, the periphery of the top including the part carrying the extension being flanged downward to embrace the top edges of the body, said extension then being reversely bent and 10

lying in proximity to the flange and slightly curved to form a spout, the spout lying to 15 one side of the can body and having its inlet substantially flush with the outer surface of the can top.

In testimony whereof I have hereunto signed my name in the presence of two subscribing witnesses.

JOHN P. EULBERG.
